UNITED STATES PATENT OFFICE.

ROBERT DAVIS, OF MODESTO, CALIFORNIA.

ATTACHMENT FOR THRASHERS.

SPECIFICATION forming part of Letters Patent No. 465,357, dated December 15, 1891.

Application filed April 15, 1891. Serial No. 389,051. (No model.)

To all whom it may concern:

Be it known that I, ROBERT DAVIS, a citizen of the United States, residing at Modesto, in the county of Stanislaus and State of California, have invented a new and useful Attachment for Thrashers, of which the following is a specification.

This invention relates to thrashing machines, and more especially to devices adapted to be connected thereto for the purpose of separating the grain from the chaff after it has passed from the thrasher.

The object of the invention is to effect improvements in devices of this character whereby less waste of grain will occur than in devices of a similar nature heretofore constructed.

To this end the invention consists of the details of construction hereinafter more fully described and claimed, and as illustrated on the two sheets of drawings, wherein—

Figure 1 is a plan view of this device complete with the cover removed. Fig. 2 is a central longitudinal section thereof. Fig. 3 is a perspective view of the riddle and its operating devices. Fig. 4 is a similar view of my improved chaff-carrier, partly broken away, the better to show its construction. Fig. 5 is an elevation of the front end of the machine, showing the upper end of the return-trough and the switch for directing the grain therefrom to either end of the cylinder. Fig. 6 shows several views of the weight-box for automatically shifting the switch.

Referring to the said drawings, the letter F designates the frame of this device, which is of any preferred size and material, and A is an air-blast located therein, in the present instance being a rotary fan directing its blast through the shaking-screen or riddle S. Across the lower end of this riddle is a return-auger R, above which is a picker P, and the auger delivers through one side of the frame-work into a return trough or elevator E. This elevator delivers the grain and chaff into a switch-box B, whence it is dropped onto the thrashing-cylinder or onto the grain-carrier G, and is returned thereby to the riddle S to be again treated.

C is my improved chaff-carrier, which is hinged just in rear of the return-auger, and

which carries off the chaff that has passed from the riddle.

The specific construction of these parts is as follows: The frame F is of course adapted to receive the several parts of this device, and the fan A is preferably of the shape and relative size shown, its mouth directing the blast of air through the riddle S. This riddle is best seen in Fig. 3 and comprises a curved sieve or screen 1, held in proper shape by a wire frame-work 2. Across the lower end of this sieve is a number of fingers 3. Links 4 connect this lower end with the frame F, so as to permit the sieve to swing longitudinally, and one of these links is extended upwardly in an arm 5, which is connected by a pitman 6 with a crank 7 on a sprocket-wheel 8. The latter is keyed to a shaft 9, having a similar crank 7 on its other end outside the frame F, and these cranks 7 are connected by vertical links 4' with the upper corners of the frame-work 2 and preferably set opposite to each other. By this construction when the sprocket-wheel 8 is driven by a chain belt from some wheel on the machine the lower end of the sieve will be caused to move longitudinally, while the upper end will be caused to move vertically and also to wabble, and the resultant compound movement of the riddle will very effectually separate the grain from the chaff. The grain which drops through the riddle falls on an inclined board I and is carried by a delivery-auger D to a suitable receptacle in the ordinary manner. The air-blast from the fan blowing through the sieve 1 drives the chaff over onto the chaff-carrier C, and heretofore some of the grain was often blown over with the chaff and lost. The chaff which travels down the sieve 1 is caught by the fingers 3 and prevented from falling into the return-auger R, (whose function will be hereinafter described,) and in order to prevent the accumulation of chaff upon these fingers I provide a picker P, which, as shown, is simply a rotating shaft having fingers, it being understood that these fingers pass between those at the lower end of the riddle. Thus the chaff is picked from the fingers 3 and is blown over onto the chaff-carrier.

Across the lower end of the riddle S is a trough or gutter 10, within which is located the return-auger R. This auger consists of a

rotating shaft 11 with a screw-blade 12 thereon, and as the auger turns the blade carries the grain in the trough 10 through an opening in the frame F into the return-trough or 5 elevator E, located outside the frame-work and leading to a point above the grain-carrier G. This elevator may be a rotating auger within a trough or an endless band having buckets; but its function is to carry the grain 10 and whatever chaff may be therein, which is delivered by the return-auger R, back to the grain-carrier or to the thrashing-cylinder to be re-treated. The object of this is that a more thorough separation may take place and 15 that no grain which may be embedded in the chaff, and hence not pass through the sieve 1, will be lost.

In Fig. 5 is shown a switch-box B, which is located at the front end of this device and 20 over the thrashing-cylinder. Within this box is arranged a switch 21, pivoted at 22 near its lower end and its free end adapted to move across the mouth 23 of the elevator E. Beneath this box is arranged a rectangular guideway 24, preferably composed of rods, and in 25 this guideway travels a weighted wheel 25, whose grooved periphery loosely engages said rods. At the center of this wheel is arranged a pair of oppositely-extending stub-shafts 26, and 30 27 is a pair of slotted arms rigidly secured to and depending from the lever 28, their slots loosely engaging said stub-shafts. The lever 28 is pivoted near its upper end, and a link 29 connects the ends of the switch and 35 lever, as shown. The object of this construction is that when the device is located upon a side hill, as is often the case, the weighted wheel will travel to the lower end of the box and will automatically move the switch so as 40 to cause the elevator E to deliver to the upper end of the thrashing-cylinder rather than to the lower end, as would be the case if the weight and switch were not used. The wheat and chaff are then re-thrashed, as will be ob- 45 vious, and fall upon the grain-carrier G, which is a traveling apron, whereby they are delivered onto the riddle again along with the grain which is already thrashed.

In Fig. 4 is shown my improved chaff-carrier C, which is located in rear of the return-auger R. This carrier comprises side plates 30, connected by a screen or sieve 31, and having a solid bottom 32 inclining downwardly and delivering into the trough 10 of 55 the return-auger R. 33 is a shaft extending through the frame F and through the lower ends of the side plates 30 and having a sprocket-wheel 34 upon one end, by means of which it is rotated by a suitable chain belt. 60 This shaft extends across the lower end of the sieve 31 and a companion shaft 35 extends across the upper end, its ends preferably projecting beyond the side plates 30 and moving in curved slots 36 in the sides of the frame F. By this means the carrier is pivotally mounted upon its lower shaft 33 and its upper end can be raised or lowered to set it at a

greater or less angle to the riddle, as may be desired. On the shafts 33 and 35 are sprocket-wheels 37 inside the side plates 30, and around 70 these wheels travel chain belts 38, which are connected across the carrier by slats 39, thereby forming an apron which moves in the direction of the arrow. By this means what grain and chaff may blow from the riddle 75 over onto the chaff-carrier is dragged by the slats 39 upwardly over the sieve 31, the chaff being delivered into the waste pile and the grain sifting through the sieve onto the bottom 32 and being dragged thereon by the 80 slats 39 back into the trough 10 of the return-auger R. From this point it is carried upwardly by the elevator E, re-thrashed, and again fed by the grain-carrier G to the riddle S. It will thus be seen that the grain is fed 85 from the thrashing-machine onto the riddle or shaking-screen S, through which it falls onto the inclined board I, and is delivered by the delivery-auger D to a receptacle in the usual manner; but what grain sticks in the 90 chaff and is blown by the fan off the riddle S and has heretofore been lost in this device falls upon the chaff-carrier C and is returned through the auger R and elevator E to be thrashed again. Moreover, what chaff 95 sticks in the fingers 3 of the riddle S is forced outwardly by the picker P and dropped into the auger R, when it will be subject to re-thrashing. Thus the device is very effectual and prevents any grain from being lost. I 100 also consider the specific details of construction above described highly desirable, if not essential, for use in this connection, although considerable change may be made therein without departing from the spirit of my 105 invention.

What is claimed as new is—

1. In a device of the character described, the combination, with an elevator, of a box into which said elevator delivers, a switch pivoted near its lower end at the center of the box and having its free end moving across the mouth of the elevator, and a rolling weight located in a guideway and having stub-shafts and a pivoted lever, one end connected with 110 said switch and the other end having a pair of slotted arms loosely embracing said stub-shafts, as and for the purpose set forth.

2. In a device of the character described, the combination, with an elevator, a box into 115 which said elevator delivers, and a switch pivoted near its lower end at the center of the box and moving across the mouth of said elevator, of the rectangular guideway below said box, a weighted wheel in said guideway having flanges engaging the sides thereof, stub-shafts on said wheel, a pivoted lever having a pair of slotted arms loosely engaging the stub-shafts, and a link connecting 120 said lever with the lower end of the switch, as and for the purpose set forth.

3. The herein-described riddle, the same comprising a wire frame-work 2, a sieve 3 mounted upon the same, links rising from the

four corners of said frame, a rotating shaft across the upper end thereof and having cranks on its ends connected by the upper links, the upper ends of the lower links being pivoted in the supporting frame-work, an arm rising from one of said pivoted ends, and a pitman connecting said arm with one of said cranks, the whole adapted for use as and for the purpose set forth.

10. 4. The herein-described switch-box, the same being located beneath the delivery end of a return-elevator, a switch within said box pivoted at its lower end at about the center thereof and its free end moving across the

mouth of said elevator, a rectangular open 15 guideway, a weighted wheel therein having flanges engaging the sides of the guideway, and connections between said weight and switch, as and for the purpose hereinbefore set forth. 20

In testimony that I claim the foregoing as my own I have hereto affixed my signature in presence of two witnesses.

ROBERT DAVIS.
